IRA C. McALLASTER, OF MILO, MICHIGAN.

Letters Patent No. 72,311, dated December 17, 1867.

IMPROVED TRACE-FASTENER.

The Schedule referred to in these Letters Patent and making part of the same.

TO ALL WHOM IT MAY CONCERN:

Be it known that I, IRA C. McALLASTER, of Milo, Barry county, Michigan, have invented a new and improved Tug or Trace-Fastener; and I do hereby declare that the following is a full, clear, and exact description thereof, which will enable others skilled in the art to make and use the same, reference being had to the accompanying drawings, forming part of this specification.

The present invention relates to a fastener or buckle for the tugs or traces of harness to the hames-straps. This fastener or buckle consists of a frame having side guards, which frame is fastened in any suitable manner to the outer end of the hames-strap, along its length, so that the tug or trace-strap can be drawn through it from end to end, and there secured by inserting a tongue into the proper aperture thereof, that is, at one end of a lever, arranged to slide upon a cross-pin between the side guards, and in the direction of the length of the frames, wherein such tongue is fastened by running the opposite end of the lever up over the end of the frame, where the tug or trace enters, as will be readily apparent from the detail description thereof to be now given. In the accompanying plate of drawings my improved tug or trace-fastener is illustrated—

Figure 1 being a plan or top view of the same, and of the hames and a portion of a tug-strap, and

Figure 2 a central longitudinal section, taken in the plane of the line $z z$, fig. 1.

Similar letters of reference indicate corresponding parts.

A, in the drawings, represents a hame-strap, that at one end, B, is to be fastened to the hames of a harness-collar in any suitable manner, the other end C of the said hames-strap being provided with my improved fastener or buckle D, to be now described. This fastener D consists of a frame, E, having parallel side guards F, and ear-pieces G, through which and the hames-strap rivets H are passed for fastening the frame E thereto, along which it is to extend in the direction of its length. This frame E is open at each end, and through it, entering at the end I, the tug or trace-strap J is passed and drawn into the usual loop of the hame-strap. L, the tongue to the fastener D, which tongue is, at one end of a lever or arm, M, hung by its slot a, on a cross-pin, b, of the frame D, in its cut-out portion N, between the side pieces F, where it is arranged to move or slide in the direction of the length of the frame, so that the opposite end of the lever to that which is provided with the tongue L, can be brought over and upon the surface P of the buckle-frame D, at the end where the trace-strap enters. The end of the frame where the tongue L is located, is notched or cut out at Q, to allow the tongue to set in the same, as well as cut out at R, along the hame-strap, for the tongue to set in when inserted and forced through any aperture of the tug-strap.

To use the fastener above described, insert the trace-strap in the frame D at its end I, forcing it through the frame from such end to the other, (taking care that the tongue to the lever is swung up out of its path,) and into the loop of the hame-strap. When there, secure the trace-strap by forcing the tongue L down through the aperture of the trace, then opposite thereto, and drawing the trace out sufficiently to bring the tail end of the tongue-lever over the frame at the end where the trace-strap enters it.

From the above, it is plainly obvious that the trace-strap is securely fastened and held to the hames-strap, and that it can be secured at any point where it is provided with an aperture according to the length required, and that, furthermore, to unfasten the trace, it is only necessary to slide the tongue-lever forward sufficiently for its tail end to clear the surface of the frame D, upon which it rests, when, then, pressing down such end, the tongue will be swung out and clear of the trace-strap, leaving it free to be drawn out or slid in, as is obvious, and again secured at any desired point, or removed entirely.

My improved buckle can be applied to any hames-straps, even if they have been used before with the ordinary buckles; for to attach them it is only necessary to remove the old buckle, without ripping the stitching in the strap, and then pass through the hole in the same used by the old buckle the rivet employed in my buckle, the mode of operation being similar with the girth, the back-band, however, always fastening with another buckle.

Having thus described my invention, what I claim as new, and desire to secure by Letters Patent, is—

The buckle constructed as described, consisting of the frame E, having parallel side guards F, and ear-pieces G, through which the rivets H pass, and slotted upon its upper side to receive the lever M, hung by a slot, a, on a cross-pin, b, upon which it slides, and provided with the tongue L at one end, its other end fitting upon the surface P of the buckle-frame, as herein described for the purpose specified.

IRA C. McALLASTER.
